UNITED STATES PATENT OFFICE.

WILLIAM H. DUNN, OF DENVER, COLORADO.

DEVICE FOR TESTING EYES.

Application filed December 9, 1926. Serial No. 153,637.

This invention relates to an improved optical instrument, for use by physicians and eye specialists, both as an error detector and trial frame.

5 As an error detector, it is intended for use by doctors who are not eye specialists. By its use, they can ascertain the refractive needs of their patients' eyes, and refer those who are in need of a complete refraction 10 test, to an eye specialist.

As a trial frame, the important advantage 15 of the invention, is that it includes a means whereby the person is able to support the device in his hand, while making the test, thereby overcoming the disadvantages of bringing uncomfortable weight to bear upon the nose of the patient, during the test, such as results when using the ordinary trial frame.

20 Briefly, the invention has reference to a structure of this kind which includes a substantially V-shaped supporting member of resilient formation, wherein the arms are movable toward and from each other, by a 25 manually adjustable contrivance for regulating expressly constructed heads on the outer ends of the arms in order to acquire the proper pupillary distance of the head.

The specific structural details forming the 30 features of construction will become apparent from the following description and drawings.

In the accompanying drawings forming a 35 part of this application, and in which like numerals are employed to designate like parts throughout the same:—

Figure 1 is a front elevation of an optical instrument constructed in accordance with the present invention,

40 Fig. 2 is a section taken approximately upon the plane of the line 2—2 of Fig. 1.

Fig. 3 is an enlarged sectional view in detail, taken approximately upon the plane of the line 3—3 of Fig. 1.

45 In carrying out the invention, I provide an appropriate supporting handle, generally designated by the reference character 1, the same being of V-shaped design as aforementioned. Inasmuch as it is formed of resilient metal, the arms 2 are movable toward and from each other under the action of an adjusting slide 3 which is mounted thereon.

50 Rigidly secured to the outer end of each arm is an especially constructed head 4 which includes a rigidly mounted metal disk 5 (see Fig. 2) and a rotatably mounted disk

6 of leather, or suitable material. A pivot and fastening bolt 7 serves to support a washer 8, and a retaining thumb nut 9, this bolt passing through the central axes of the 60 stationary and movable disks respectively and serving to maintain them in proper assembly.

On the inner marginal side, the metal disk 5 is provided with a sight opening 10 of appropriate diameter. The rotatable disk 6 is formed with a cooperating opening 10^a and supported on the front face adjacent this opening, is a lens holder 11. This holder, as shown in Fig. 3, comprises a body constructed to formulate three pockets for removable reception of the cylinders used in making any refractory tests.

At this time, I would direct attention to Fig. 1, wherein it will be seen that around the upper marginal half of each opening 10^a is a conventional meridian scale employed for locating the axes of the test cylinders. It will be noted that the cylinder holders 11 are disposed in a position to facilitate insertion and removal of the cylinders without interference. This is simply for rapidity and convenience in handling.

It will be noticed that in addition to the opening 10^a, each disk 6 is provided with circumferentially spaced openings in which lenses 12, 13 and 14 are fitted, and adapted to be selectively registered with the openings 10 in the stationary disks.

The lens 12 is representative of minus 90 fifty (-50); the lens 14 is representative of plus fifty (+50); and the intermediate lens 13 is indicative of plus one hundred (+100).

From the foregoing description and drawings, it will be seen that I have evolved an 95 exceptionally simple and inexpensive structure which may be employed in one instance as a novel trial frame, which is advantageous in that it includes the individual pockets or cells for taking care of the cylinders employed in making the refractive tests. The meridian scale over the blank openings aids in location of the axis of the cylinder. The slide 3 is adjustable in order to regulate the width or pupillary distance.

100 The advantages of this trial frame are that it does not rest on the nose or cling to the ears, and thereby cause discomfort. The instrument is portable and can be used anywhere that an ordinary trial case frame can 110 be used.

As an error detector, it is intended for

use by doctors who are not eye specialists. With it, they can ascertain the refractive needs of their patients' eyes and refer those who are in need of a complete refraction 5 test, to an eye specialist. In using the device, the patient may be seated the proper distance from an ordinary test card.

The detector is placed in his hand, and so adjusted in front of the eyes that the right 10 pupillary distance is obtained. This is done by having the blank openings in front of the eyes. The first test is to ascertain the smallest lines to be seen with the use of both eyes on the test type. Next the solid portion 15 of the rotary disk is turned to cover one of the blanks or openings to make a single eye test. This is repeated with the other eye. Then the minus and plus lenses are brought into place simultaneously and separately, and the doctor can tell by the answers 20 to the questions whether or not defects occur.

Of course, there are certain rules and regulations to be followed in using the device, but these need not be explained, as they 25 will be better understood from the actual use of the instrument.

It is believed that a clear understanding of the construction, as well as the operation and use of the invention will be had from the foregoing description and drawings. Therefore, a more lengthy description is thought unnecessary.

Having thus described my invention, what I claim as new is:—

As a new product of manufacture, an eye testing device comprising a resilient V-shaped handle, a slide mounted upon the arms of the handle and adapted to move them toward and from each other, stationary 40 disks carried by the outer ends of the arms, said disks being provided with blank sight openings, complementary disks rotatable and mounted upon the first named disks, said complementary disks being provided with 45 openings for registry with said blank openings and further provided with additional openings in which lenses of various intensities are fitted, and multiple cylinder holders associated with the first-named openings 50 on the rotatable disks.

In testimony whereof I affix my signature.

WILLIAM H. DUNN.
